UNITED STATES PATENT OFFICE.

JOHN ELLIS PEARSON, OF MIMOSA, NORTH CAROLINA.

AEROPLANE.

1,378,895.

Specification of Letters Patent. Patented May 24, 1921.

Application filed February 13, 1920. Serial No. 358,512.

To all whom it may concern:

Be it known that I, JOHN ELLIS PEARSON, a citizen of the United States, and a resident of Mimosa, in the State of North Carolina, 5 have invented certain new and useful Improvements in Aeroplanes, of which the following is a specification.

My invention relates to aeroplanes, and a purpose of my invention is the provision 10 of an aeroplane having greater plane surface and greater carrying capacity than aeroplanes heretofore proposed without increasing the weight of the machine.

I will describe one form of aeroplane embodying my invention and will then point 15 out the novel features thereof in claims.

In the accompanying drawings:

Figure 1 is a view showing in side elevation one form of aeroplane embodying my 20 invention.

Fig. 2 is a central longitudinal sectional view of the aeroplane shown in Fig. 1.

Fig. 3 is a transverse sectional view taken on the line 3—3 of Fig. 2.

25 Fig. 4 is a fragmentary detail view showing in side elevation the driving means and supporting means for one of the propellers of the aeroplane shown in the preceding views.

30 Fig. 5 is an enlarged detail view of the mechanism for controlling and actuating the rudder of the aeroplane.

Similar reference characters refer to similar parts in each of the several views.

35 Referring specifically to the drawings F designates a fuselage upon which are supported a vertically disposed plane P and a pair of superposed horizontally disposed planes P' and P''. The fuselage is supported upon a chassis comprising a forward carriage C and a rear carriage C' each of which is provided with wheels W. At the rear of the planes P, P' and P'' is a rudder R, and disposed upon opposite sides at points adjacent the opposite ends of the fuselage F are four propellers L', L'', etc. At the forward end of the fuselage F is another propeller L''.

40 As shown in Figs. 1, 2 and 3, the fuselage F comprises an inner body 15 of rectangular formation in cross section and an outer body 16 of tubular formation which surrounds and is rigidly connected to the inner body. The opposite ends of the inner body 15 project beyond the ends of the outer body 16 and are tapered as indicated at 15^a, such end

portions being utilized for the storage of gasoline. Engines E are carried within the inner body 15 and are operatively connected to the several propellers L in the 60 manner shown to advantage in Fig. 1. As shown in Fig. 4, the propellers L', L'', L''' and L^a are each supported upon standards 17 secured to the outer body 16 of the fuselage. The propeller L^a is driven from its 65 corresponding engines through a shaft 18 which as shown in Fig. 1 extends above the forward end portion 15^a.

As illustrated to advantage in Fig. 3, the vertical plane P consists of an upper section 70 19 and a lower section 20, both of which are rigidly connected to the outer body 16 at points diametrically opposite to each other. As shown in Fig. 1, the sections 19 and 20 are coextensive in length with the 75 fuselage F, the lower section 20 having its forward and rear ends inclined inwardly as shown for the purpose of allowing of the safe landing and rising of the aeroplane.

The upper horizontal plane P is partly 80 supported upon the upper section 19 and intersects the latter at right angles as clearly shown in Fig. 3. The lower horizontal plane P^a is formed of two sections 21 and 22 which extend from the fuselage at diametrically 85 opposite points and are supported against vertical movement by guys S connected to the sections and to the sections 19 and 20 of the vertical plane P, in the manner shown in Fig. 3. The horizontal planes P' and P^a 90 are formed in sections as shown in Fig. 2 and are maintained in spaced parallel relation to each other by struts B arranged at intervals between the two. The struts B are of elliptical formation in cross section 95 as is the usual formation of such members. As shown in Fig. 2, the lower horizontal plane P^a is provided at its rear end with ailerons A which are for the usual purpose of preserving the side to side balance of the 100 aeroplane. As shown in Fig. 2, a wire cable K extends around the edges of the planes P' and P^a and is connected to the outer ends of the tapered portions 15^a, the purpose of this arrangement being to provide the necessary reinforcement for the planes. 105

Referring now to Figs. 2 and 5, the rudder R is shown as comprising a direction plane 23 and an elevation plane 24 disposed at right angles to the latter and rigidly secured thereto for movement therewith. The rudder R is movably supported upon 110

the rear end of the fuselage F by a ball and socket joint 25 so as to allow the universal movement of the rod. The mechanism for controlling and actuating the rudder comprises in the present instance two pairs of rods 26 pivotally connected at their rear ends to the rudder and provided at their forward ends with screw threaded portions 26^a upon which work worm gears 27. The worm gears 27 in turn mesh with worms 28 supported upon the opposite ends of actuating shafts 29. In the present instance, only one shaft 29 is shown in the drawings for actuating one pair of rods 26. Each shaft 29 is provided with a wheel 30 by means of which the shaft can be manually rotated to actuate the worms 28 which in turn rotate the worm gears 27 to effect a longitudinal movement of the rods 26 in one direction or the other according as the shaft 29 is rotated in one direction or the other. By this arrangement the rudder R can be moved to any desired position to effect the proper steering of the aeroplane.

From the foregoing description, taken in conjunction with the accompanying drawings, it will be manifest that in operation, the aeroplane is propelled with uniformity through the small propellers L', L², L³ and L⁴, the propeller L⁵ serving to drive the aeroplane centrally along its longitudinal axis and effecting in a degree an equalization of the propulsion of the other propellers. As the planes P, P' and P² are extensive in length with the fuselage it will be manifest that an aeroplane of great rigidity is provided with a lifting surface of great area. It will also be noted, the vertical plane P serves to preserve the side to side balance of the aeroplane.

The operators of the aeroplane are housed within the inner body 15 of the fuselage where they are completely protected from the elements. Access to the fuselage is gained through a door 31 as shown in Fig. 2, the forward end of the fuselage being provided with observation windows 32.

Although I have herein shown and de-

scribed only one form of aeroplane embodying my invention, it is to be understood that various changes and modifications may be made herein without departing from the spirit of the invention and the spirit and scope of the appended claims.

What I claim is:

1. An aeroplane comprising, a fuselage, a vertical plane comprising an upper section and a lower section arranged at diametrically opposite points on said fuselage and coextensive in length therewith, a horizontal plane comprising sections disposed at diametrically opposite points of the fuselage and coextensive in length therewith, and a second horizontal plane disposed above the first horizontal plane and the fuselage.

2. An aeroplane comprising, a fuselage including an inner body of rectangular formation and an outer body of cylindrical formation, a vertical plane arranged along the longitudinal axis of the fuselage, a horizontal plane arranged along the longitudinal axis of the fuselage and disposed at right angles to the vertical plane.

3. An aeroplane comprising, a fuselage including an inner body of rectangular formation and an outer body of cylindrical formation, a vertical plane comprising an upper section and a lower section arranged at diametrically opposite points on the fuselage and coextensive in length therewith, a horizontal plane comprising sections disposed at diametrically opposite points in the fuselage and coextensive in length therewith, a second horizontal plane disposed above the first horizontal plane and above the fuselage, and propellers at the forward end of the fuselage and between the horizontal planes at corresponding points on the opposite sides of the fuselage.

4. A fuselage for aeroplanes comprising, an inner body of angular formation, an outer body of cylindrical formation, and conical end portions formed on the cylindrical body.

JOHN ELLIS PEARSON.
